Attorneys

UNITED STATES PATENT OFFICE

JOHN E. RENFER, OF CLEVELAND, OHIO, ASSIGNOR TO THE CLEVELAND ROCK DRILL COMPANY, OF CLEVELAND, OHIO

VALVE-STEM LOCK

Application filed March 13, 1929. Serial No. 346,662.

The present invention is directed to improvements in valve stem locks.

The primary object of the invention is to provide a device of this character so constructed that a valve stem can be held positively against longitudinal movement, but may be freely rotated when desired.

Another object of the invention is to provide a device of this kind primarily designed for use in connection with the valve of a rock drill, but not necessarily limited to such use.

With these and other objects in view, as will appear as the description proceeds, the invention accordingly consists in the novel features of construction and arrangement of parts to be hereinafter fully described and pointed out in the appended claims.

In the accompanying drawing, in which similar characters of reference denote like and corresponding parts throughout the several views thereof:—

Figure 1 is a sectional view through the valve chest of a rock drill, illustrating the application of this invention.

Figure 2 is an end elevation of the valve.

Figure 3 is a section taken on the line 3—3 of Figure 1.

Figure 4 is a view partly in elevation and partly in section of a modified form of the invention.

Figure 5 is a section taken on the line 5—5 of Figure 4.

Referring to the drawing, 1 designates a portion of a drill cylinder in which is reciprocable the piston hammer 2, the movement of which is controlled by the spool valve 3 in the manner disclosed in the patent to Gustave M. Nell, No. 1,603,705 issued October 19, 1926.

It is desired at times to hold the hammer and valve in such positions that a continuous blast of air will pass through the drill steel to blow the cuttings from the hole being drilled, and in order to accomplish this the shank 4 has its rear end formed with a head 6 provided with an axial counter-bore 7 in which is rotatably mounted a valve shank 8, and since the present invention is directed to the means for rotatably retaining the stem in place, a detailed description of the man-

ner in which the shank co-operates with the parts of the drill is not deemed necessary.

The head 6 fits in one end of the valve chest 9, the bore 7 thereof having opening thereinto a slot 10 formed transversely of said head. 55 The shank is provided with an annular groove 11 and a handle 12, said handle carrying a spring pressed latch 13 for selective engagement with the recesses 14 and 15 formed in the adjacent face of the head 6 in order that the stem can be held positively in adjusted positions.

Removably engaged in the slot 10 is a locking plate 16 having a circular seat 17 and resultant extensions 18 adapted to enter the groove 11 to prevent longitudinal movement of the shank 8, but permitting rotation thereof when desired.

The outer end of the plate 16 is extended from the slot 10 a sufficient distance to engage 70 a boss 19 or any other adjacent part of the drill body to prevent accidental disengagement of the plate from the slot. Obviously the plate can be readily removed when the drill is disassembled.

In the modified form of the invention the head 6 is provided with diametrically opposed slots 20 for receiving the locking plates 21, said head having an exterior annular groove 22. The plates 21 have their outer ends curved, as at 23, in order that they will lie in a plane with the groove 22 so that when the split resilient ring 24 is snapped in the groove 22 it will engage the outer ends of the plates and hold the same interlocked in the annular groove 11 of the shank 8. Since the ring 24 can be removed and replaced, the plates 21 may be easily and quickly applied or removed.

From the foregoing, it is thought that the operation and many advantages of the herein described invention will be apparent to those skilled in the art without further description, and it will be of course understood that the shape and proportions may be changed 85 or varied, and minor details in construction may be resorted to without departure from the spirit of the invention.

What is claimed is:—

1. The combination with a valve chest, of

a shank therein, a spool valve slidable on the shank, said shank having a head provided with an axial bore, a valve stem rotatable in the bore, and a locking plate removably engaged in the head and having interlocking engagement with the stem, as and for the purpose set forth.

2. The combination with a valve chest, of a shank fixed therein, a spool valve slidable on the shank, said shank having a head upon one end and fitted in the end of the chest, said head having an axial bore, a valve stem rotatable in the bore and having an annular groove formed therein, a locking plate mounted in the head and having engagement with the groove, said plate serving to prevent longitudinal movement of the stem, but permitting free rotation thereof.

3. The combination with a valve chest, of a shank fixed therein, a valve movable thereon, said shank having a head upon one end and fitted in the chest, said head having a transverse slot formed therein, a valve stem rotatable in the head and having an annular groove therein, a locking plate removably mounted in the slot for engagement with the stem.

4. The combination with a valve chest, of a shank fixed therein, a valve movable on the shank, said shank having a head for engagement in one end of the chest, a valve stem rotatable in the head, locking plates carried by the head and having interlocking engagement with the stem, means supporting the chest and engaged with the plates for holding the same engaged in the head.

In testimony whereof I affix my signature.
JOHN E. RENFER.
